CLAIM

The ornamental design for a trunk, as shown and described.

DESCRIPTION

FIG. 1 is a front view of a trunk;

FIG. 2 is a right side view of the trunk shown in FIG. 1;

FIG. 3 is a back view of the trunk shown in FIG. 1;

FIG. 4 is a left side view of the trunk shown in FIG. 1;

FIG. 5 is a top view of the trunk shown in FIG. 1;

FIG. 6 is a bottom view of the trunk shown in FIG. 1; and,

FIG. 7 is a perspective view of the trunk shown in FIG. 1.

The broken lines illustrate portions of the trunk and form no part of the claimed design.
